UNITED STATES PATENT OFFICE.

GEORGE W. CAMPBELL, OF HARTFORD, CONNECTICUT, ASSIGNOR TO UNDERWOOD
TYPEWRITER COMPANY, OF NEW YORK, N. Y., A CORPORATION OF DELAWARE.

TYPEWRITING MACHINE.

Application filed September 24, 1919. Serial No. 325,928.

To all whom it may concern:

Be it known that I, GEORGE W. CAMPBELL, a citizen of the United States, residing in Hartford, in the county of Hartford and 5 State of Connecticut, have invented certain new and useful Improvements in Typewriting Machines, of which the following is a specification.

This invention relates to typewriting machines of the class in which a central guide is provided near the printing point, and in 10 which the type-bars have guiding projections at the types, which are individually parallel with the types and all adapted to enter said guide, which is usually placed vertically under the printing point.

At the extreme sides of the type-bar system, this central guide is not so efficient as it is with the type-bars at the middle of the 20 system; and an object of the invention is therefore to provide means for more efficiently guiding a few of the type-bars at the extreme sides of the system. To this end, there is provided an auxiliary type-bar 25 guide on each side of the usual central type-guide. One auxiliary type-bar guide serves for say four type-bars at one side of the system, and the auxiliary guide at the other side serves for the same number of type-bars at the other side of the system. The 30 types which are mounted upon these side type-bars are not provided with projecting guides or lugs, and hence are not guided by said central guide; but the side type-bars 35 themselves are adapted to enter the auxiliary guides. These auxiliary guides control the tendency of these side bars to vibrate laterally, and they may be simply and inexpensively formed upon the bracket which 40 holds the central type-guide.

Other features and advantages will hereinafter appear.

In the accompanying drawings,

Figure 1 is a central sectional elevation 45 of a typewriting machine of the portable front-strike class, embodying the present improvements.

Figure 2 is a perspective side view of the 50 central type-guide provided with auxiliary guides for some of the side type-bars.

Figure 3 is a plan of the type system, type-guiding device and platen.

Figure 4 is a front elevation of the type-guide and a portion of the type-bar segment,

showing particularly the arrangement of the 55 side type-bars.

Figure 5 is a similar view to illustrate the manner in which most of the type-bars are guided in the usual central guide.

Figure 6 is a diagram to illustrate one of 60 the four left-hand type-bars in its printing position.

The machine comprises the usual banks of keys 10 mounted upon levers 11, which have pin-and-slot connections 12 with bell-crank 13, the latter connected by links 14 to the type-bars 15, all mounted upon a fulcrum rod 16, which is fixed in a segment 17, the latter having radial slots 18 in which the type-bars work. All the type-bars are provided with type blocks 19 secured thereon, each block usually carrying three types 20. The type blocks are usually soldered upon the free ends of the type-bars. At each of these type-blocks or types is a projecting guide or fin 21 which is formed on the type-bar and is parallel with the type, and which, when the type is in printing position, Figure 5, occupies a slotted central guide 22, which is mounted upon a fixed bracket 23 placed just below the printing point on the platen 24, said bracket being secured to the segment 17 by means of screws 25. At Figure 5 the guiding projection 21 upon the type is seen as held between the jaws of the type-guide 22. About three-fourths of the type-bars are guided in this manner; the types being bent at progressively increasing angles to the type-bars, as seen at Figure 3, so that all of the types and the guiding projections when in printing position stand vertically, as at Figure 5, even though the type-bars radiate at different angles. In the printing position, as shown in Figure 5, the bends in the type-bars 15 occur approximately at the lower ends of the type blocks 19, while the guides 21 project below the type blocks.

For the four bars 15^a at the extreme ends of the type-bar system, the guiding projections 21 are omitted from the types, and the central type-guide 22 is therefore not used. For these bars there are provided two auxiliary guides 26, between the jaws of which the bodies of the type-bars enter, as at Figure 4. Each type-bar body may, if desired, be formed with a projection or widening 27 to enter the guide, and this flat projecting

portion of the type-bar may be slightly twisted to accommodate it to the auxiliary guide, as will be understood from Figure 6. As most clearly appears in Figures 4 and 6, 5 the bends in the type-bars 15^a occur above the lower ends of the type blocks 19, in the printing position, so that these type-bars may be guided in the auxiliary guides 26 close up to the type blocks 19 at the sides 10 thereof and near the printing point. The type-bars 15^a, at the printing position, radiate substantially from the printing point, and the auxiliary guides 26 engage these type-bars 15^a between the bends therein and 15 the pivot 16, but close to the bends, as shown in Figure 4.

The auxiliary guides 26 are shown as risers on and may form a fork extending up from the main guiding bracket 23, and may 20 have diagonal slots 28 corresponding to the positions of the type-bars which enter the same; that is, these auxiliary slots diverge substantially radially downwardly and outwardly from about the printing point.

25 It will be seen that the auxiliary guides overcome the tendency of the type-bars to rattle or spring laterally, or to twist, so that better printing and more satisfactory operation are secured.

30 Variations may be resorted to within the scope of the invention, and portions of the improvements may be used without others.

Having thus described my invention, I claim:

35 1. In a front-strike typewriting machine, the combination with a system of pivoted type-bars, of a three-part type-guide, comprising a central part to guide the middle type-bars in the system, said central part 40 being positioned below the printing point, and the middle type-bars being provided at the types with projections in line therewith and at angles to the bars, to enter said central part, and opposite guiding parts 45 above the central part, at the sides thereof, near the printing point and to be directly engaged by type-bars at the sides of the system.

2. In a front-strike typewriting machine, 50 the combination with a system of pivoted type-bars, of a central type-guide for the main portion of the type-bars in the system, said central guide being in a line with the types at the printing point, and said main 55 type-bars having at their types guiding projections extending therefrom to enter said guide, and type-bar guides near the printing point and at the sides of said central type-guide and auxiliary thereto, to be 60 directly engageable by type-bars at the sides of the system, said side type-bars having bends at their type ends, and said auxiliary guides being engageable by said type-bars between said bends and the type-bar pivots.

65 3. In a front-strike typewriting machine,

the combination with a system of pivoted type-bars, of a central type-guide for the main portion of the type-bars in the system, said central guide being in a line with the types at the printing point, and said main 70 type-bars having at their types guiding projections extending therefrom to enter said guide, type-bar guides near the printing point and at the sides of said central type-guide and auxiliary thereto, to be directly engageable by type-bars at the sides of the system, a bracket upon which said central guide is mounted, and risers on said bracket at the sides of said central guide, 75 and provided with jaws to form said auxiliary guides.

4. In a front-strike typewriting machine, the combination with a system of pivoted type-bars, of a central type-guide for the main portion of the type-bars in the system, 80 said central guide being in a line with the types at the printing point, and said main type-bars having at their types guiding projections extending therefrom to enter said guide, type-bar guides near the printing point and at the sides of said central type-guide and auxiliary thereto, to be directly engageable by type-bars at the sides of the system, a bracket upon which said central guide is mounted, and risers on said bracket at the sides of said central guide, 85 and provided with jaws to form said auxiliary guides, said jaws inclining about radially of the printing point.

90 5. In a front-strike typewriting machine, 100 the combination with a system of pivoted type-bars, of a three-part type-guide comprising a central part to guide the middle type-bars in the system, said central part having a vertical slot below the printing point, and the middle type-bars being provided at their types with projections in line therewith and at angles to the bars to enter said slot of the central part, and opposite guiding parts above the central part and at 105 the sides thereof and comprising slots to receive directly the type-bars at the sides of the system.

110 6. In a front-strike typewriting machine, 115 the combination with a system of pivoted type-bars, of a central type-guide for the main portion of the type-bars in the system, said central guide being in a line with the types at the printing point, and said main type-bars having at their types guiding projections extending therefrom to enter said guide, and type-bar guides near the printing point and at the sides of said central type-guide and auxiliary thereto, to be directly engageable by type-bars at the 120 sides of the system, said side type-bars having bends at their type-ends, and said auxiliary guides being engageable by said type-bars between said bends and the type-bar pivots, said side type-bars being provided 125

with flat guiding projections extending directly therefrom to enter said auxiliary type-guides.

7. In a front-strike typewriting machine, 5 the combination with a system of pivoted type-bars, of a central type-guide for the main portion of the type-bars in the system, said central guide being in a line with the types brought to the printing point, and 10 the type-bars of said main portion having type-blocks set at such angles thereon as to be in alignment with the central guide, so that guiding projections extending from the type-bars at their type-blocks and in 15 line therewith will enter said guide, and type-bar guides near the printing point and

at the sides of said central type-guide and auxiliary thereto, to be directly engageable by type-bars at the extreme sides of the system, the last-mentioned type-bars having 20 type-blocks thereon arranged to come to a substantially vertical printing position and having bends so positioned at their type-ends that, when swung to their printing positions, said auxiliary guides will be engaged thereby between said bends and the type-bar pivots and near to said bends. 25

GEORGE W. CAMPBELL.
